CUP AND SAUCER COMBINATION

William Shefts, New York, N. Y.

Application December 14, 1939, Serial No. 309,120

3 Claims. (Cl. 65—13)

The present invention is concerned with a novel cup and saucer combination.

Frequently, when one is served with a liquid refreshment, such as coffee or tea, the saucer is found partly filled with the liquid which therefore contacts with and adheres to the bottom of the cup so that in raising the cup to the lips of the user he or she is subjected to the annoyance of having the excess liquid drip upon his or her clothing, table cloth, etc.

It is accordingly one of the principal objects of my invention to suitably shape and construct the cup and saucer whereby the above disadvantage may be overcome. I accomplish this by providing the saucer with a trough or well with which there communicate a plurality of conveniently located channels or gutters.

It often happens with the present type of cup and saucer, unless the server or waiter exercises a reasonable degree of care, that the cup "swims" around the saucer, spilling the liquid, and it may even result in the cup dropping to the floor.

Another important object of my invention therefore is the provision of positive gripping means whereby in transit the cup is retained or immovably held within the saucer to preclude slippage. For that reason the cup and saucer construction according to my invention is admirable for use on airplanes, railroad dining cars, auto trailers and other conveyances.

The novel features characteristic of my invention are set forth with particularity in the appended claims. The invention itself, however, both as to its construction and combination of elements together with other objects and advantages thereof, will best be understood by reference to the following description taken in connection with the accompanying drawing in which—

Fig. 1 is a cross sectional view on the line 1—1 of Fig. 2 showing the cup retained within the trough of the saucer.

Fig. 2 is a plan view of the saucer showing the connecting channels.

Fig. 3 shows a partial view in perspective of a modified form of trough for the saucer, and

Fig. 4 is a partial cross-sectional view of the modification disclosed in Fig. 3 showing the cup in position.

In the several figures like or similar elements are designated by the same reference characters.

Referring now to Fig. 1, the cup 1 is of usual construction except that at its base or bottom there is provided an undercut rim portion 2 of reduced diameter which is adapted to have a

close fit within the centrally located trough or well 3 formed in the saucer 4. Encircling the rim portion 2 on the under surface of the cup is a shoulder or ledge 2' which is adapted to cooperate with the upper surface of the saucer adjacent the trough in a manner to be more fully described hereinafter. The side wall 5 of the trough or well is preferably given a slight taper, as shown, to facilitate manufacture, and also to permit quicker drying, as when allowed to stand on edge in a drying rack.

Also formed in the saucer are a plurality of channels or gutters 6 which slope from the upper or top surface 7 of the saucer downwardly to communicate with the trough 3. As best shown in Fig. 2 each channel or gutter is formed of the two halves or faces 8 and 8' which converge at the center line 9, the latter and the faces sloping downwardly as illustrated in Fig. 1.

The bottom edge of the cup marked 10 in Fig. 1, and which is also the outer edge of the shoulder 2', is represented in Fig. 2 by the dot and dash circle 10. It will be observed that there are several points of contact between the cup and saucer. These are indicated by the elliptically-shaped portions 11 of the upper surface 7 of the saucer, which portions are suitably distributed around the upper edge of the trough 3. Between each pair of adjacent contacting portions 11, there is one of the channels 6 which are adapted to carry off, somewhat in accordance with the water-shed principle, any excess liquid that may have happened to be spilled onto the surface of the saucer. The snug fit between the rim portion 2 at the bottom of the cup and the upper portion of the wall 5 of the trough provides positive means for retaining the cup on the saucer in transit and precludes slippage therebetween. Also, the depth of the trough is suitably chosen so that with the cup on the position shown appreciable liquid will be accumulated within the trough without touching the bottom of the cup.

In the modification shown in Figs. 3 and 4 the trough 3' is comprised of a tapered side wall 5' from which at regular intervals there project a plurality of lugs 12 (only one being shown) upon the upper surface 11' of which the shoulder 2' of the cup is adapted to rest, as shown in Fig. 4. Of course, it will be understood that any suitable number of lugs, such as three, four or more, may be employed. It will be observed that with the cup in position a plurality of channels are provided for drawing off the excess liquid from the upper surface 7 of the saucer into

the trough 3', the mouth of each such channel being formed by the upper edge of 5', the bottom edge 10 of the cup and the opposing sides of a pair of adjacent lugs 12.

While I have shown and described preferred embodiments of the invention, it will be understood that modifications and changes may be made without departing from the spirit and scope of the invention.

What I claim as new and desire to secure by Letters Patent is:

1. A saucer and a cup adapted to be used in combination therewith whereby excess liquid spilled into the saucer is prevented from adhering to the base of the cup, said saucer comprising a trough, a plurality of V-shaped channels formed in the saucer and communicating with the trough, the bottom of the cup being provided with an undercut rim portion which is adapted to have a close fit with the upper portion of the trough. 15

2. A saucer and a cup adapted to be used in combination therewith whereby liquid in the saucer is prevented from adhering to the base of the cup, said saucer comprising a trough having a bottom wall and a tapered side wall, a 20

plurality of channels formed in the upper surface of the saucer and sloping downwardly to join with the upper portion of the trough side wall, and means formed at the bottom of the cup adapted to engage the upper rim portion of the trough side wall whereby the cup is relatively closely fitted within the trough and in spaced relation with respect to the bottom wall of the trough. 5

3. A cup and saucer combination whereby excess liquid in the saucer is prevented from adhering to the base of the cup, said cup having an undercut rim portion and an annular shoulder encircling the rim portion, said saucer being provided with a trough having a tapered side wall, a plurality of channels formed in the upper surface of the saucer and sloping downwardly to join with the upper portion of the trough side wall, a plurality of spaced-apart surfaces formed between adjacent channels, the annular shoulder of the cup adapted to rest on said spaced-apart surfaces and the cup rim portion adapted to fit closely with the upper annular portion of the trough side wall. 25
